<img alt="Technical cross-sectional diagram of a mechanical assembly, labeled Fig. 9. The diagram shows a complex arrangement of parts including a main body, various shafts, bearings, and a lever system. Key labeled parts include: 11, 270, 284, 271, 277, 273, 272, 12, 274, 286, 280, 281, 282, 279, 278, 283, 16, 179, 288, 112, 111, 289, 290, 288a, 291, 102, 103, 262, 263, 272, 270, 119, 123, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 200, 201, 202, 203, 204, 205, 206, 207, 208, 209, 2010, 2011, 2012, 2013, 2014, 2015, 2016, 2017, 2018, 2019, 2020, 2021, 2022, 2023, KNITTING MACHINE

Robert H. Lawson, Pawtucket, R. I., assignor to
Hemphill Company, Central Falls, R. I., a corporation of Massachusetts

Application March 29, 1930, Serial No. 439,976

15 Claims. (Cl. 66—43)

This invention relates to knitting machines for producing split fabric and also to the method of producing same, and the resulting fabric. More particularly the invention relates to circular, automatic knitting machines adapted to knit split foot hosiery, together with the process and resulting fabric.

In order that the principle of the invention may be readily understood, I have shown, merely as an example, one embodiment of the mechanism, and shall set forth the preferred manner of operating the mechanism to practice the process.

I have represented the invention as applied to several different types of hosiery and with several different types of foot and other reinforcements.

In the drawings:

Fig. 1 is a side elevation of a lady's stocking knit in accordance with my invention;

Fig. 2 is a similar view of a half hose showing a narrow sole;

Fig. 3 is a similar elevation but of the foot and ankle only, of a stocking embodying my invention, but provided with a regular sole;

Fig. 4 is a front elevation of a circular knitting machine embodying my invention;

Fig. 4a is a detail in vertical section on the line 4a—4a of Fig. 4 and looking toward the right in said figure;

Fig. 4b is a detail, partly in longitudinal vertical section and partly in elevation, of the main pattern drum;

Fig. 5 is a left hand elevation of the said machine;

Fig. 6 is a right hand elevation of the machine;

Fig. 6a is a detail view of a part shown in Fig. 6;

Fig. 7 is a rear elevation of the machine;

Fig. 8 is a view, partly in plan, but with the machine frame shown in horizontal section on the line 8—8, Fig. 5;

Fig. 8a is a development of the cam drum for the takeups;

Fig. 9 is a front elevation of the knitting head of the machine upon an enlarged scale;

Fig. 10 is a plan view of the knitting machine head shown in Fig. 9;

Fig. 11 is a plan view, partly in horizontal section, through the needle cylinder and frame, but mainly in plan, the section taken on the line 11—11, Fig. 9;

Fig. 12 is a view similar to Fig. 11 but taken on the section line 12—12, Fig. 9, and showing in plan all the jack cams;

Fig. 13 is a left hand end elevation of the knit-

ting head of the machine and some of the parts therebelow;

Fig. 14 is a rear elevation of the knitting head;

Figs. 14a, 14b, 14c are details in side elevation showing the latch releasing cam and the flopper cam for operating the long butt needles;

Fig. 15 is a vertical transverse section taken through the knitting head and certain of the parts therebelow upon the line 15—15, Fig. 10;

Fig. 16 is a detail, mainly in plan and partly in section, of the top of the needle cylinder and the sleeve within the said cylinder;

Fig. 17 is an elevation, partly in section, of the auxiliary cam block viewing the same from the inside thereof, together with the slide for raising the sleeve within the needle cylinder;

Fig. 17a is a plan view of the cam adjustment shown in Fig. 17;

Fig. 18 is a plan view of the mechanism for operating the yarn changing lever for making the reinforced high splice and the top of the toe;

Fig. 19 is an elevation of the construction shown in Fig. 18 looking toward the left in said figure, and showing the yarn change lever bracket;

Fig. 20 is a detail in vertical section of the yarn change lever bracket;

Fig. 21 is a side view of the entire fashioning wheel particularly showing the independent fashioning wheel for ladies' stockings and the fashioning levers acted on thereby;

Fig. 22 is a plan view of the construction shown in Fig. 21;

Fig. 23 is a horizontal section taken through the fashioning wheel on the lines 23—23, Fig. 21;

Fig. 24 is a detail in section on the line 24—24, Fig. 21;

Fig. 25 is a plan view of the drum and take-up control levers and showing also levers for operating the narrow sole mechanism and the reinforced high splice mechanism;

Fig. 26 is a side elevation of the construction shown in Fig. 25;

Fig. 27 is a front elevation of the construction shown in Fig. 25;

Fig. 28 is a detail in plan and in transverse section of the slide for operating the auxiliary cam block and the slide for the sleeve inside the needle cylinder, the section being on the line 28—28, Fig. 13;

Fig. 29 is a plan view, but partly in horizontal section, of the sinker cam ring and adjacent parts;

- Fig. 47 is a similar development showing the position of the parts in knitting a foot with a narrow sole, when the movement of reciprocation is in the opposite direction.
- 45 My invention, while in certain aspects thereof is applicable to the production of numerous fabrics as well as several parts of hosiery, more particularly relates to means for producing split work in the ankle portion or the foot portion, or both, of stockings and socks or half hose, and to the method or process by which such hosiery or other fabric is produced as well as to the fabric itself. The machine is particularly adapted to the knitting of ladies' stockings and men's half hose of high grade.
- 50 While within the scope and purpose of my invention the results may be secured by knitting mechanisms of different types, I have chosen, without limiting myself thereto, to disclose that embodiment of the invention which is a circular hosiery knitting machine of the so-called Banner type.
- 55 I will, for convenience of description, refer to the patent to Augustin Gagne, No. 1,673,764, dated June 12, 1928, wherein is disclosed a Ban-
- ner split foot hosiery machine of the latch needle type. Generally speaking, during the formation of split work substantially one half of the ankle portion is knitted upon one set of needles and the remaining portion upon the rest of the needles, two yarns being fed, one at the regular side and the other at the auxiliary side, said two yarns being interknitted at desirably opposite suture seams. While the structure of the suture seams may, of course, be widely varied within the scope of my invention, and while my invention is not limited to the production of any particular structure of suture seam, the structure of suture seam knitted by the mechanism shown in this embodiment of my invention is the same, or essentially the same, as that shown in Fig. 15 of the said patent to Gagne, No. 1,673,764. That is to say, in one course at each side of the stocking there is a loop and a partial loop of one yarn and in the next preceding, as well as in the next following course, there is a single loop only of the other yarn. This structure is continued in such alternation of loop with partial loop and single loop throughout the continuation of split work.
- 60 Before referring to the structure of the machine, I will briefly set forth the characteristics of the hosiery knitted upon the machine of the present invention, and in doing so, will make reference to Figs. 1, 2 and 3.
- The welt 1 of the stocking shown in Fig. 1 is knitted by any desired yarn at the regular or main knitting side, as, for example, through the yarn finger A in Fig. 10, and thereupon the ring top 1a is knitted from a yarn supplied at the regular or main knitting side. Upon the completion of the ring top 1a, the circular portion 2 of the leg is knitted by a yarn introduced through the auxiliary side (that is to say, through the yarn finger B in Fig. 10). This differs from the construction shown in the said Gagne patent and from other patents and practices of the prior art so far as I am aware, and the advantages thereof will be apparent from the ensuing description.
- 65 The circular knitting is continued with the use of yarn or silk or other suitable character introduced through the yarn finger B until a point 3—3 is reached (namely, at the top of the high splice). The knitting is now changed to reciprocating knitting. The high splice portion of the stocking is knitted at the regular knitting cam side. Such high splice occupies one half the circle of needles, such knitting being done upon the short butt needles. The said high splice may have the portion 4 thereof knitted with a single yarn, or if desired with two yarns which, for example, may be fed in a plating relation. If the portion 4 is knitted with a single yarn, then the portion 5 is knitted with two yarns, but if the portion 4 is knitted with two yarns, then the portion 5 is knitted with three yarns. The portion 5, whether of two or three yarns, may terminate at the top of the heel or may extend down into the heel, as indicated at 5'. The front portion of the instep, in the disclosed embodiment of my invention, is knitted at the auxiliary side and with the same yarn that is used in knitting the circular portion of the leg down to the high splice. This gives a regularity of stitch and an evenness of structure and appearance which is not obtainable in constructions heretofore employed where a change of yarn was made when the line 3—3 was reached.

The heel 6 is knitted by narrowing and widening in the usual manner, but the extent of the heel is a small plurality (preferably about three needles at each side) less than one half the entire circle of needles, so that each suture seam 7 is removed several wales from the inner point of the heel. 5

Each suture seam 7 is desirably continued through the foot, and may be continued either 10 along the same wale, as is indicated at 8 in Fig. 3, or the suture seam on each side may be dropped down to the line 9 in order that the suture seams of the foot may not be observed when low slippers are worn. This applies particularly to ladies' 15 stockings. The position and length of the line 9 may be varied as desired. The extent to which the suture seams in the foot are or may be dropped below the median line at the side of the foot can, of course, be widely varied within the 20 scope of my invention, but preferably I drop them about sixteen needles at each side, and have indicated means for doing this in Fig. 33. The dropped portion 9 of the suture seams at the side of the foot may continue to the toe or the 25 forward part thereof may be at a higher elevation, as shown for example at 10 in Fig. 1. In advance of the suture seams 10 I desirably knit a ring toe 11 upon all the needles by circular work, and then knit the toe 12 by narrowing and 30 widening and introduce a reinforcing yarn wherever desired, as, for example, to reinforce the area 13.

In knitting the stocking shown in Fig. 1 and referring to Fig. 10, the high splice may be knitted 35 by the yarn supplied through the yarn finger C, the reinforcing yarn for the area 5, 5' may be knitted by a yarn supplied through the yarn finger D at the regular side, the heel and toe may be knitted by a yarn introduced through a 40 yarn finger E at the regular side, and the sole of the foot may be knitted by a yarn introduced through a yarn finger F at the regular side.

The half hose shown in Fig. 2 is desirably 45 knitted in the same manner as the lady's stocking shown in Fig. 1, and the same numerals are used for the same parts. The part 1', corresponding to the welt 1 of the lady's stocking, is termed the rib top. The ring top 1a is provided in both 50 the lady's stocking and the half hose.

It will be understood from the foregoing description that the yarn, desirably silk, introduced 55 through the yarn finger B at the auxiliary side is used to knit the circular part 2 of the leg, also the front portion of the instep and the top of the foot down to the ring toe. The result is a uniformity of stitch not obtainable where, as heretofore, a substitution of yarn has been made when beginning the ankle. In making the change 60 of yarn in the prior constructions, the new yarn was, of course, supplied from another cone, and it was impossible to feed the same under exactly 65 the same conditions as the preceding yarn.

Referring now to the main portions of the machine, and first to Figs. 4 to 7 inclusive, the machine has a frame 14, within which is mounted a 70 needle cylinder 15 preferably, though not necessarily, revolvable, and a non-revolvable cam carrier or support 16, 17 carrying knitting cam sets 16' and 17'. Mounted in the frame 14 is a main shaft 18 carrying suitable pulleys 19, 20, 21 respectively employed as high speed, slow speed and loose pulley. A pattern shaft 22 is mounted in said frame and has thereon an appropriate cam or 75 pattern drum 23. Upon said pattern drum is a

peripheral rib or cam 24 which engages the follower 25 carried by a pivoted clutch shifting lever 26 connected with the usual clutch 27 for shifting from reciprocating to rotary driving instrumentalities and vice versa, said latter instrumentalities being well known features of Hemphill Company or Banner patents, as, for example, said Gagne Patent No. 1,673,764 and others, and for further information concerning the same reference may be had thereto. The follower 25 is adapted to travel through cross slots 28 from one side of the rib 24 to the other, so as to effect the shifting of said clutch members. One of such cross slots is shown in Fig. 4. By means of the mechanism just described, the needle cylinder 15 is adapted to be given, at certain times in the knitting operation, a continuous rotary movement, as, for example, during the knitting of the leg of the stockings, as hereinbefore described. At other times the said needle cylinder or the 20 cam carrier (if that be the movable member) is given a to and fro or reciprocating movement not only during the knitting of the heel and toe pockets of the stocking, but also desirably and as herein disclosed during the knitting of the ankle 25 portion and the foot.

Such reciprocating movement during the formation of the ankle or the foot, or both, causes, as hereinbefore stated, the introduction of knitting yarns at both the main and the auxiliary 30 sides of the machine for the formation of suture seams which are, as disclosed in this embodiment of the invention, along the wales preferably oppositely spaced from each other. I have chosen in this embodiment of my invention to show the formation of suture seams only along parallel lines and without crossing wales, as in my Patent No. 1,458,833, June 12, 1923, although the formation of wales along inclined lines is within the scope of my invention. 35

Within the scope of my invention a stocking may be commenced at the top of the leg or at the toe, but I will describe only that embodiment of the invention wherein the knitting is commenced at the top of the leg part without limiting myself thereto and will describe only that embodiment of the invention where the suture seams are two in number, being at opposite sides of the stocking and confined to and extending along two widely spaced wales of the fabric without crossing other wales. 45

By means of the mechanism just described, the needle cylinder 15 is adapted to be given at certain times in the knitting operation a continuous rotary movement, as, for example, during the 55 knitting of the leg of the stocking or half hose, while at other times said needle cylinder is given a to and fro or reciprocating movement during the knitting of the heel and the toe pockets of the stocking, and in the split work areas of the ankle and foot, and although the present embodiment of the invention has been described as having a revolving needle cylinder and stationary cams, obviously within the spirit and scope of the invention the same is not limited to this 60 construction.

While my invention is not limited thereto, I 65 preferably operate with latch needles of the independent needle type and use long butt needles to knit at the auxiliary side and short butt needles to knit at the main, regular or primary side. I have, in Fig. 32, indicated within a bracket 29 the long butt needles at the auxiliary side and within a bracket 30 the short butt needles at the 70 main, regular, or primary side. 75

In order to provide that the corners of the heel shall be spaced from the suture seams, and in order to provide for dropping the side portions 9 of the suture seams in the foot below the longitudinal median line of the side of the foot, I have provided the following construction represented in Fig. 33.

In said figure are shown sixteen jacks next to the long butt needles at each end of the said long butt series. One set of said sixteen jacks is indicated at 31 and the other set of sixteen jacks is indicated at 32 in said Fig. 33. Said jacks are all under short butt needles. Three of each of said two sets of jacks (namely, those indicated 15 at 33, 34) have long butts and the remainder of said jacks have short butts. The said long butt jacks 33, 34 pertain to the six needles which, at the corners of the heel pocket, are between said corners and the two suture seams 7. The heel 20 is made upon six less needles than heretofore. If it is desired to provide the suture seams 8 along the longitudinal median line of the sides of the foot, I prefer to retain the thirteen short butt jacks at both sides of the knitting cylinder, and 25 if I do so, I cam up the levers which control the said jacks from the cams upon the plain cam disk, but if desired I may leave said jacks in the machine.

The knitting cam set 16' upon the primary, regular or main side is desirably the same as in the said Gagne Patent No. 1,673,764, as shown in Figs. 10 to 13 inclusive. That is to say (referring to Figs. 40 and 47), I provide usual stitch cams 35, 36, a lower central guide cam 37 and an upper central guide member 38. The inner faces of the said cams are concaved and lie normally in a plane coinciding with the outer face of the needle cylinder 15, said cams being withdrawn from this position only when it is desired to level the needles for transferring or to withdraw the cams to get at the needles of the cylinder for the purpose of withdrawing or replacing needles.

purpose of withdrawing or replacing needles.

At the auxiliary side I provide a pair of stitch cams 39, 40, an upper guide cam 41 and a guard cam 42 for said upper guide cam. The inner faces of said several cams are concaved and are arranged normally to lie in a plane coinciding substantially with the plane of the outer face of the needle cylinder, which plane also coincides with the plane of the inner faces of the cams of said primary set. Below the said cams 39 to 42 at the auxiliary side, I provide a single cam 43 which extends from the front raise cam 44 at the left viewing Fig. 40 to the rear raise cam 45 toward the right. The said cam 43 is provided with projections 46, 47, affording riding angles between which and the stitch cams 39, 40 respectively the needles are guided in the knitting operation. The entire structure 43, 44, 46, 47, may be and desirably is adjusted by a micrometer screw adjustment so that its circumferential position with respect to the needle circle may be very accurately positioned.

In Fig. 17a, I have represented a suitable form of micrometer screw adjustment for the said cam 43. In said figure is shown a slotted pivoted stud 47a which is tapped into the plate 17, and there is also represented a pivoted stud 47b tapped into the structure of the said cam 43. Received in the slotted portion of the stud 47a is a screw 47c having a knurled head 47d, a threaded portion 47e, and a shoulder 47f. Rotative movement of said screw, therefore, very accurately adjusts the said cam 43 and so positions the projections 46, 47 thereof as to equalize

the knitting points and thus provide for an exact evenness of stitches in both directions of reciprocating knitting.

I will next describe the means for supporting the auxiliary knitting cam set and adjusting the height thereof automatically during the knitting of those parts of the stocking or half hose that are to be shaped, particularly the ankle portion, and then will describe the means for elevating the sinkers to provide a uniformity of stitch length at the two sides and the means for operating and controlling the sinkers during the knitting operation.

Referring first to Figs. 5, 13, 15, 17, the auxiliary knitting cam set, as clearly shown in Fig. 17, is secured to and carried by the plate 17, beneath which is an angle piece or bracket 48 secured by screws 49 to a vertical slide 50 which at its lower end is guided by a vertical depending bracket 51, shown most clearly in Figs. 13 and 15. The said bracket is longitudinally slotted near its lower end, as shown at 52, for the reception of a pin 53 threaded to the said slide 50 near the lower end of the latter. The said pin 53 is acted upon by the end 54 of a lever 55 pivoted at 56 upon an extension of the said guiding bracket 51. As shown most clearly in Fig. 5, the said lever 55 has a downwardly extending arm 57 which at its lower end has a fixed piece 58 within which are guided a series of slides 59, 60, 61, 62, capable of being adjusted respectively by the corresponding set screws 59', 60', 61', 62'. The said slides 59 to 62 are adapted at the proper times to be acted upon by cams upon the fashioning wheel 63 and upon the cam drum 64, to be hereinafter more particularly referred to. Within the needle cylinder 15 is mounted a sleeve 65, the purpose whereof is the same as that shown in a co-pending application of Lawson & Lawson, Ser. No. 330,906. The said sleeve 65 turns with the needle cylinder by means of pins 66 passing through a flange 67 at the bottom of said sleeve and tapped into the needle cylinder gear 68.

The said sleeve 65 rests upon a bracket 69 45
which has secured thereto a bracket 70 secured
to a slide 71 having a face to face relation with
the bracket 50. Below the bracket 70 is a sta-
tionary cover plate 72 having a screw 73 which
is connected by coil spring 74 to a screw 75 in
the slide 71, and therefore tends to move said
slide downward. Secured in the lower part of
said slide 71 is a pin 76 threaded to the slide
71 extending through a slot 76' of the cover
plate 72, the said pin 76 being acted upon by the
end 77 of a lever 78 pivoted at 56. Said lever
78 has a downwardly extending arm 79, as shown
in Fig. 7, which at its lower end has a foot 79a
within which is guided a slide 79b adjusted by
a screw 79c, which engages a cam on the drum
64, to be hereinafter referred to. 60

Referring again to the sleeve 65, it is pointed out that the same fits the needle cylinder relatively tightly but loosely enough to permit the ready slight axial adjustment which is imparted thereto at the commencement and at the termination of the split work. The said sleeve at the top is provided with two plates 80, 81, shown most clearly in Fig. 16, and curved so as to be concentric with the inner face of the said sleeve 65. Said plates are secured to said sleeve by means of screws 82 passing through elongated horizontal slots 83, whereby said plates may be moved slightly to and from each other, thereby exactly conforming in circumferential extent 70

with the entire series of long butt needles and their sinkers. While the circumferential extent of said two plates may be varied to suit different types of machines, they are here shown as together occupying 180° of the needle cylinder, as clearly appears from Fig. 16. At their meeting ends, said two plates have an interengaging formation 84.

The sleeve 65 is moved slightly upwardly at the very commencement of the split work and is restored to its normal or lower position precisely at the end thereof. The upward movement of the said sleeve 65 acts to tilt or rock slightly upward the long butt sinkers by engaging the same beneath their lower guiding edges. In Fig. 15, however, the position of the parts is such that the sinkers are not tilted upwardly.

The sinkers are shown most clearly in Figs. 30 and 31, and are indicated generally by the numeral 85. There are long butt sinkers at the side of the cylinder having the long butt needles, and there are short butt sinkers at the side of the cylinder of the short butt needles. The said sinkers are carried by the sinker cam ring 86, which is of the same construction that is shown in the said Lawson & Lawson application. The cap plate of the sinker cam ring is indicated at 87.

As shown most clearly in Figs. 29, 30, 31, it is provided with a transverse groove 88 receiving a slide 89 overlying which is a cap 90 capable of slight adjustment by means of the screws 91 and the slots 92. At the inner end of said slide 89 is attached a segmentally shaped cam 93, which, as shown most clearly in Fig. 30, takes over the stems of the long butt sinkers and engages and presses against the vertical back face 94 of said sinkers, so as to move them radially inward to hold down the work at the auxiliary side while the knitting of the heel and the toe is proceeding at the main side.

The said slide 89 is provided with a depending pin 95 engaged at all times by a piece 96 of arc shape. Said piece has a stem 97 slidingly received in a slot in a bracket 98.

The said stem 97 is provided with a lateral projection 99 to be moved by the lever 100 pivoted at 101 upon the bracket 98. As shown most clearly in Fig. 15, the said lever 100 acts upon the yarn guide D at the auxiliary side to throw the same down into feeding position at the proper times.

As previously stated, jacks are used beneath certain of the short butt needles at both ends 55 of the semi-circle of such needles. In order to control and operate said jacks at the desired times certain cams are employed, the structure of which I will describe, and thereafter I will set forth in detail the times at which the said 60 cams act and the precise purposes of such action.

Referring more particularly to Fig. 12, I have there represented a series of six cams at 102, 103, 104, 105, 106, 107, circumferentially arranged in such order. These cams are also 65 shown in the several developments of the cams in Figs. 40 to 47.

The cam 102 has a stem 108 provided with an arcuate slot 109 receiving a pin 110 upon a transversely arranged slide 111 which is supported under a bracket 112 by screw 111a in slots 111b, said bracket 112 being secured to the under side of the cam carrier or support 16 at the main or primary knitting side. The said slide 111 has pivotally connected at one end thereof 70 at 113 an arm 114 of a lever pivoted at 115 on

the bracket 115a, the opposite end of said lever being pivotally connected at 116 to a link 117 operated in a manner to be hereinafter described.

The two cams 103 and 107 are stationary cams of a triangular construction in cross section, as shown in Fig. 40, etc.

The cam 104 is mounted for rocking and also radial movement upon a stem 118 which extends through a bearing 119 and is provided with a lateral pin 120 received in an arcuate or inclined slot 121 in said bearing 119. The outer end of the stem 118 has attached thereto an arm 122 to which is secured a link 123 connected at its other end to a lever arm 124 fast upon a horizontal rod 125 mounted in suitable bearings 126, 127 and extending across the head of the machine. The means for operating said rod 125 will be more fully described hereinafter.

The cam 105, which is of triangular shape, as shown clearly in Figs. 40, etc., is provided with a stem or flange 128 secured by screws 129 passing through slots in a lever 130 which is pivoted at 131 upon a housing carrying a stop 130' to limit the inward movement of the lever 130, and which at its opposite end 132 is connected to a horizontally extending link 133 operated in a manner to be hereinafter more fully described.

The cam 106, which is also of triangular shape, as shown in Figs. 40, etc., is provided with a stem 134 that is guided in a housing 135 whereon the lever 130 is pivoted. The said stem 134 has pinned thereto at 136 a lever 137 itself pivoted at 138. Said lever 137 at its opposite end is pivotally secured at 139 to a horizontal link 140 which extends to and is pivotally secured to 35 a lever arm 141 fast upon the said rod 125 herefore referred to.

None of the jacks is brought into action until the termination of the suture seams 7 of Figs. 1 and 2, excepting that (as hereinafter stated) they are brought into action for the last course of the ring top. At such time (namely, at the termination of the suture seam 7) it is necessary to provide means to insure the positioning of the corners of the pockets a small plurality of wales from said suture seams. It is for this purpose that the three long butt jacks 33 and the three long butt jacks 34 of Fig. 33 are provided. When that point in the knitting operation is reached, the cam 102 is moved radially inward but far enough only to engage the six long butt jacks 33, 34. The cams 103, 107 serve to guide the said jacks onto the slopes of the said cam 102 in both directions of reciprocation.

The other jacks (namely, the twenty-six short butt jacks shown in Fig. 13) are to be brought into action when the character of drop side suture seams 9 of Figs. 1 and 2 is employed. To accomplish this result, the operation is as follows:

First, the cam 102 is moved in the remaining distance to engage the butts of all the jacks (namely, both the short butts and the long butts), so that the needles with sixteen jacks on each side will be raised in time so as not to knit on the regular side in the first course after changing out of the heel. Then the two cams 104, 106 are moved inward, the cam 104 being also rocked downward so that the said two cams assume the position shown in Figs. 46 and 47.

In the direction of reciprocating movement toward the left viewing Fig. 46 in making the narrow sole with the jacks, both long and short butts ride up the cam 104. In the direction of reciprocation toward the right in making said nar-

row sole, all the jacks, both long and short, ride up the cam 106.

It is, of course, to be understood that in knitting the regular sole (such as shown in Fig. 3) the said cams 104, 106 are inoperative.

Viewing Figs 1 and 3, the said two cams 104 and 106 remain in operation throughout the formation of the dropped part 9 of the suture seam and at the termination of the dropped part 9 they are drawn out of action for one course and then are thrown in for one course, and then again down out of action and remain out during the formation of the raised or elevated part 10 of the suture seams. The said in and out movements of the said cams at the termination of the dropped part 9 of the suture seams cause to be knitted into the stocking the float thread formed at this point, namely, when each suture seam is shifted from the dropped position 9 to the more elevated position 10. Such float threads would otherwise be formed at the two sides of the stocking at this point and would constitute a serious defect.

The cam 105 acts upon and elevates the two set of long butt jacks 33 and 34 when the split foot 10 is completed, so as to prevent an eyelet forming therein at one point, which is indicated at 142 in Figs. 1, 2 and 3.

An eyelet would also be formed when the yarn is changed from the ring top 1a to commence the leg 2. All said six long butt jacks are drawn up at such time by the cam 105 to prevent the formation of such an eyelet when changing from the foot yarn to the ring toe yarn.

Next in order of description is that of the so-called fashioning drum. Referring to Figs. 5 to 8, 13, 17 and 21 to 24, the fashioning drum, already briefly referred to, is loosely mounted upon a shaft 143 itself mounted in suitable bearings 144, 145 at the rear of the machine. The purpose of the said drum, used primarily in the knitting of ladies' stockings, is to shorten the stitch length automatically and at frequently recurring intervals during the knitting of the calf and angle portion thereof, thus providing a suitable shaping of the stocking. It is to be understood, however, that the said drum may be employed in knitting men's half hose, for the same purpose.

The shaft 143 has fast thereon a sprocket wheel 146 surrounding which is a sprocket chain 147 also passing about an equal sized sprocket wheel 148 fast upon the usual pattern drum shaft 22. A sprocket wheel 148a on an arm 148b takes care of all slack in the chain 147. The rotative movements of the drum 64 are under the control of mechanism which in this embodiment of the invention give a ratcheting movement to the drum whenever fashioning should be effected. For this purpose, the following means is provided.

The regular pattern chain of the machine is provided with a suitable link or formation which at the proper time imparts short movements or rotation to the sprocket wheel 148 which, through the sprocket chain 147, turns slightly the sprocket 146 and the drum 64. Upon said drum 64, as shown most clearly in Fig. 24, is a lug 150 which in said slight initial or short movement of the drum 64 engages the lug 151 upon the fashioning wheel 63 and moves said wheel sufficiently to move the lug 152 away from the depending pawl 153, shown most clearly in Figs. 5 and 13.

The said fashioning wheel 63 is also provided with a lug 153' upon which the pawl 153 rides 75 when the fashioning wheel has been sufficiently

ratcheted around, thus removing said pawl from engagement with the teeth of the ratchet 156.

Upon the regular "104" gear shaft 154 is mounted an eccentric 155 carrying said pawl 153, so that in the constant rotation of the "104" gear shaft 154 the pawl 153 (so long as the lug 152 does not prevent functioning of said pawl 153) engages the teeth 156 of the fashioning wheel 63, and therefore presents successive portions of a cam surface 157 to the slide 62 heretofore referred to. The said cam 157 is of constantly increasing height, as is evident from Fig. 21. The said cam is pivoted for adjustment upon the screw 158 and is provided with a radial slot 159 into which takes a screw 160. The adjusting movement of the said cam 157 is effected through an adjusting screw 161. This gives an exceedingly accurate adjustment to the said cam, and through the action of said cam upon the slide 62, the auxiliary cam block plate 17 is lifted as heretofore described, thereby shortening or tightening the stitches at the auxiliary side.

Fast upon the said shaft 143 is the drum 64 which has thereon four circumferential lines or rows of cam formations 61a, 60a, 59a, 79d, to act respectively upon the slides 61, 60, 59, 79b heretofore described. The purpose of the slide 61, which is primarily used in the knitting of men's half hose, is to change (shorten) the stitch length. By a single movement of the said slide 61, the stitch length is shortened as, for example, immediately upon coming out of the ring top, and such shortening continues effective down to the commencement of the high splice, shown in Figs. 2 and 3.

The purpose of the slide 60 is to make a further shortening of the stitch length for and during the knitting of the high splice (that is, through the areas 5, 5', of Figs. 1, 2 and 3).

If it be desired to use the fashioning wheel 63 in part during the knitting of half hose, the cam 157 may be set through adjustment of the screw 161, so that said cam will commence to act upon the slide 62 during some intermediate part of the circumferential length of the said cam 157.

If, during the knitting of men's hose, it is desired not to use the fashioning wheel 63, the slide 62 may be rendered inactive through adjustment of the said screw 62' thereof.

The slide 79b is for the purpose of raising the sleeve 65 within the needle cylinder, shown in Fig. 15, and the connections for operating which have already been described. The said sleeve 65 is in a raised position during all of the knitting of the high splice, and this will be evident from a comparison of the position of the cams on Fig. 22. The said sleeve 65 is also in elevated position during the knitting of the regular split sole, shown in Fig. 3, but said sleeve is in its depressed position during the knitting of the narrower sole, shown in Figs. 1 and 2. For this purpose an additional cam is fastened to the drum 64 circumferentially beyond the cam 79c.

I shall next refer to the means for introducing the reinforcing yarn for the high splice and for the toe, and for such purpose will refer particularly to Figs. 4, 6, 7, 18, 19, 20. The same yarn is preferably used for reinforcing both the high splice and the toe. Such yarn is, of course, introduced during reciprocating knitting, so that the yarn is knitted in from one lateral edge of the reinforcing area to the other without the formation of float threads, as will be perfectly evident to those familiar with the knitting of hosiery by split work.

At the rear of the machine (as shown most clearly in the rear elevation, Fig. 7, and also in the side elevation, Fig. 6) there is provided a bracket 162 with upstanding end portions 163, 5 164, wherein is mounted for rocking movement a shaft 165 having thereon a finger or lever arm 166 extending downwardly and adapted to rest upon two main cam pieces 167—167, 168—168, which are fast upon a disk 169 on the "104" gear 10 shaft 154. The said two cam pieces 167, 168 are respectively adjustable circumferentially to and from each other through the provision of circumferential slots 170 into which take screws 171. The said lever arm 166 is held in contact with 15 the said cams by suitable coil spring 172 connected to a pin upon the frame. During the knitting of the leg the reinforcing yarn lever is held out of action by the wire 171a connected to the pawl 171b resting on a cam 171c on the 20 pattern drum 23, but when going into the high splice, said lever arm 166 drops into the spaces 167a, 168a between the cam sections 167, 168, and the reinforcing yarn finger is dropped down into action, the pawl 171b having moved off the 25 cam 171c. Therefore, the area of the reinforcement is determined by the shape and position of the cams 167, 168.

Also fast upon said shaft 165 adjacent to the lever arm 166 is a lever arm 173, shown most 30 clearly in Figs. 6 and 19. Said lever arm has at its free end a bolt 174 received in a longitudinal slot 175 in a lever 176 pivoted at 177 upon a bracket 115a. Said lever 176 extends through a lateral opening 178 in a housing 179 wherein 35 are the series of wires 180 which extend down to the levers that rest upon the cams of the main pattern drum of the Banner machine to control the yarn guides. In the construction herein shown, the lever 176 at its inner end has 40 pivotally connected thereto at 181 an upright link 182 which, as shown most clearly in Fig. 20, is pivotally connected at 183 to the lever 184 controlling the movement into and out of action of the yarn guide finger D shown in Fig. 10, and 45 the function whereof has already been described. As shown most clearly in Figs. 7 and 18, there is fast upon one end of the shaft 165 a spool 185 having a pathway 186 for the reception of a pin 187 upon the upper end of a bell crank lever 188 50 pivoted at 189 upon an arm 188a secured to the upright bracket portion 164. The other arm of said lever is pivotally connected at 190 to a long, downwardly extending link 191 which, as shown most clearly in Figs. 7, 25, 27, is connected at 55 192 to the lever 193, being one of a series of levers pivoted upon the stud 194. Surrounding the said rod 165, as shown most clearly in Fig. 18, is a coil spring 195, which is held at one end by a collar 196 fast upon the said shaft 165. The 60 purpose of the said spring is, when the shaft has been moved toward the right viewing Fig. 18, to restore the same to its former position at the proper time. It will be noted that the pin 174 is, as shown in Fig. 18, elongated so that when 65 the shaft 165 and the parts fast thereon are moved longitudinally, said pin is not removed from the slot 175.

I shall next describe the drum which controls the take-ups for various yarns as well as the 70 reinforcing mechanism and the narrow sole determining mechanism, and in so doing shall refer to Figs. 8a, 25, 26, 27.

As clearly shown in Fig. 25, there are loosely provided upon the stud 194 six levers 197, 198, 75 199, 200, 193, 201. The lever 197 controls the

reinforcing yarn; the lever 198 controls the sole yarn; the lever 199 controls the heel and toe yarn, and the lever 200 controls the mercerized, high splice yarn, it being noted that, as herein-after described, through a branch thereof, the high splice silk yarn is also controlled by this same lever. In certain cases, it is desirable to introduce a single high splice yarn only, as a mercerized yarn, whereas in other cases it is desirable to introduce two high splice yarns, as, for example, one of mercerized and one of silk. 10

The lever 193, as already described, controls the reinforcing mechanism, and the lever 201 controls the narrow sole producing mechanism. 15

I shall next describe the take-ups and in so doing shall refer to Figs. 27 and 34 to 39. In Fig. 37, I have represented four upright wires 197', 198', 199', 200', which are connected respectively to the levers 197, 198, 199, 200, previously described. Each of the yarns is provided with a suitable 20 guide eye mounted upon a slender spring wire, and each of those wires is under the control of its take-up with the exception that the wire 202, shown in Figs. 34 and 37, is not provided with a take-up control. It is, however, provided with a tension wheel 202a carried by an arm 203. The other four yarns referred to are provided with tension wheels 204, 205, 206, 207, clearly shown in Fig. 5 and also in Fig. 34. Said tension wheels are carried in a bracket 208 fast upon the upright creel rod 209. 25

In Fig. 34, I have represented one yarn guide eye 210 carried by a spring wire 211 pivoted at 212. This construction is the same for each of the yarn guide eyes that is under the control 35 of a take-up. The wire 211 is mounted in a hub 213 rigid with which is a projection 214 to which is secured a downwardly extending wire 215 having connected thereto a coil spring 216 itself connected to an eye in the wire 217 upon 40 a bracket 218 on the creel rod. 40

It will be observed that each take-up wire 197' to 200', as the case may be, has a bent upper end 219 taking over the proper wire 211 to hold the same down into the position shown in Fig. 34 when the yarn has not been used. The wire 211 is held in the position shown in Fig. 21, when the proper lever, as, for example, 197, is resting upon the surface of the drum 220 of Figs. 26 and 27, and not upon one of the cams 50 of said figures. The connections of all the wires 197' to 200' are the same, it being noted, however, viewing Fig. 39, that the wire 200' has fast thereto a rod 221 which in turn has fast thereto a wire 222, the upper bent end whereof 55 takes over the wire which controls the introduction of the silk high splice yarn, if the latter be used.

The take-up drum 220 has been described, and Fig. 8a is a development of the surface of said drum. The cams are provided upon said surface at the proper point to control the several yarns and, as they may be mainly of the usual construction, it is not necessary to refer thereto, excepting with respect to two new cams 222a, 222b. 60 The purpose of said cams will be understood by reference to Figs. 1, 2 and 3. It has already been stated that in knitting the rear part of the instep portion, a single yarn is provided for the part 4 and an additional yarn for the high splice 5 70 (or even two additional yarns). Also it is desirable to have the said high splice area extend into the heel, as indicated at 5'. When the top of the heel is reached, it is necessary to withdraw from action the yarn by which the part 4 75

is knitted and to open the binder to receive and cut said yarn whereupon the heel yarn is substituted. At the same time the yarn or yarns which knit the high splice area 5 are received in said binder and cut, but are immediately restored to action, so that in reality there is no course or partial course where the areas 5 and 5a merge that is not provided with the said high splice yarn or yarns. During the brief instant in which the yarn or yarns for the high splice area 5 is in the binder, it is necessary to lock down the take-up for the said yarn or yarns of the high splice area, but also to prevent any pull upon said yarn or yarns that would result in drawing them out from the binder. This is the purpose of the cams 22a. The drum 220 is advanced one kick or impulse at this time through the action of the heel and toe dog 222c which acts on the lug 260b at this time. Such one kick or impulse of the said drum moves the drum so that the take-up is no longer locked as it was by the stops between the lugs 222a, 222b, but rides upon the said lug 222b and is unlocked.

Viewing Figs. 34 and 38, it will be observed that at 222a, 222b, there are provided two studs on the hub of the structure carrying the take-up wires. The stud 222a pivotally supports two levers 222c each having a hammer 222d, and the stud 222b pivotally supports two levers 222e each having a similar hammer. The lever 222c which is provided for the yarn at the auxiliary side rests at its end 222f upon a cam 222g on the hub 213 that pertains to the take-up wire for the said yarn at the auxiliary side. The purpose of the said cam is to control the time at which the hammer for that particular lever 222c engages with the anvil member or rests beneath the same.

I shall next describe the means for operating the cams 104, 106, and for that purpose shall refer to Figs. 7, 8a, 12, 13, 14. As previously stated, the cams 104, 106 are operated from the shaft 125. Said shaft has depending therefrom an arm 223, shown most clearly in Fig. 13. To said arm is pivotally connected a link 224 shown most clearly in Fig. 12. Said link is pivotally connected at 225 to one arm of a bell crank lever 226 pivoted at 227. To the other arm of the bell crank lever 226 is connected at 228 a coil spring 229 connected at the other end at 230 to a bracket 231 upon the framing. Said spring 229 tends to hold the bell crank lever 226 in the position shown in Fig. 12 against the action of a lever 232, clearly shown in Fig. 13 as pivoted at 233 in depending ears 231a of said bracket 231. Said lever 232 has a depending arm 234.

Upon the "104" gear shaft 154, as shown most clearly in Figs. 13 and 14, is a disk 235 whereon are mounted two oppositely positioned cams 236, 237. The shaft 233 is adapted by means presently to be described to be moved in the ears 231a, and therefore to move laterally the lever 232 with its depending arm 234. Said arm 234 is therefore adapted to rest either upon the peripheral edge of the disk 235 (as shown in Fig. 14) or upon the cams 236, 237, or to occupy a position shown in dotted lines to the right of the cam (viewing Fig. 14), and therefore not be influenced by either said disk or by its cam.

When the finger or lever arm 234 rests upon the disk as in Fig. 14, the lever arm 232 occupies the position shown in Fig. 12. When the said finger 234 is moved to a position so that it is neither upon the disk nor upon the cams, the spring 229 moves the bell crank lever 226 in a clockwise direction, thereby slightly rocking the

shaft 125 and moving the cams 104, 106 into action.

When the arm 234 is in dotted line position, Fig. 14, the spring 233a will move the shaft 233 at the proper time. The purpose of the cam 236 is to allow the arm 234 to ride on its outer surface and also against the side of the disk 235. This will move cams 104, 106 out for one course, then the arm 234 drops into the space 236a for one course, moving the cams 104, 106 in for one course, then the arm 234 is lifted to the height of the periphery of the disk 235.

It has been stated that the shaft 233 is adapted to be slid in its bearings. For this purpose, it is provided with a spool 238 in the groove of which takes a pin 239 upon a bell crank lever 240 pivoted at 241 upon a bracket 242 which itself is secured to the ears 231a of the bracket 231. A coil spring 233a surrounding the shaft 233 tends to move the said shaft toward the left, viewing Fig. 14. To move said shaft in the opposite direction, the bell crank lever 240 has connected thereto at 244 a depending link 245 which, as shown in Fig. 7, extends downward to and is connected to the lever 201 shown in Fig. 25. Said lever 201 is operated by the cam controlling the narrow sole mechanism shown in Fig. 8a at 246.

I shall next describe the means for operating the cam 102 and for that purpose shall refer to Figs. 4, 6a and 12. As clearly shown in Fig. 12 and as already described, the cam 102 is operated by the slide 111 and its connections 114 to 117. The link 117, as shown most clearly in Figs. 6 and 6a, is pivotally connected at 247 to a bell crank lever 248 pivoted at 249 upon a bracket 250. To the other arm of said bell crank lever is pivotally connected at 251 a long depending link 252, which, as most clearly shown in Fig. 6, is pivotally connected at its lower end at 253 to a lever 254. Said lever 254 is pivoted at 255 on a bracket 256. The opposite free end of said lever 254 has a toe 257 resting upon the stop motion wheel 258 fast on the main pattern shaft 22. Said disk controls the shipper mechanism in the usual manner, and in addition has thereon two lugs or elevations 259, 260, shown most clearly in Fig. 6. Said lug or elevation 259 acts at the proper time to move in the said cam 102, so that the two sets of three long butt jacks may be elevated. Said cam or elevation 260 acts subsequently to elevate all the jacks for the purpose already described.

Referring to Fig. 6, the stop motion wheel 258 is provided, in addition to the cams 259, 260, with two cams 260a, 260b. The purpose of the cam 260a is to start the action of the widening pick at the proper time to widen the toe, so that the needles will be of even number. The purpose of the cam 260b is to advance the said stop motion wheel 258 to work the take-up when changing from the high splice to the heel.

I shall next describe the means for moving into action the cam which is to pull all the needles down at the corners of the heel pocket 6, and for such purpose shall refer to Figs. 4, 9, 11. The cam referred to is indicated at 261 in Fig. 11. It is mounted for in and out or substantially radial movement with respect to the needle cylinder in a housing 262. The stem 263 of said lever is provided with a pin 264 engaged by an arm 265 of a bell crank lever pivoted at 266, the opposite arm 267 of said bell crank lever having pivotally connected thereto at 268 a horizontally extending link 269 which, at its opposite end, is pivotally connected at 270 to an arm 271 upon

75

a stud shaft on a stud 272. Rigid with said arm 271 is another arm 273 which has pivotally connected at its end, as shown most clearly in Fig. 9, a depending rod 274 extending downwardly, as shown most clearly in Fig. 4, and which has pivotally connected at its lower end a pawl 275 adapted to rest upon the chain 276, so as to be operated upon by the proper lug or lugs thereon. Surrounding the upper end of the rod 274 is a coil spring 277 tending to move the said rod upwardly. The purpose of the said cam 261 is the same as the corresponding cam disclosed in my co-pending application Serial No. 288,856. It will be understood that as three short butt needles 10 on each side are elevated with the long butt needles, it is necessary to pull all the needles down so as to get the said three needles on each side down with the remaining short butt needles, so as to have one half of all the needles for use in the heel 15 and toe.

I shall next describe the means for pulling the knitting cam out of action in going into the leg, and for this purpose shall refer to Figs. 4, 4a, 4b, 5, 9 and 11, and to a development or diagram of 20 the knitting operation, such, for example, as Figs. 40 and 41.

The knitting cam, which is the one referred to as going out of action when going into the leg, is the knitting cam 35, shown in the diagram, 30 Fig. 40, where the cam is shown as in action, and in Fig. 41, where it is shown as out of action. The purpose of moving the said cam out of action when going into the leg from the ring top is to cause the knitting of the leg to be done at the auxiliary side. Heretofore so far as I am aware, in a stocking knitted by split work the circular part of the leg has always been knitted at the primary side. I have already pointed out that by knitting the leg upon the auxiliary side, the 35 necessity is avoided at the commencement of the split work of changing the yarn by which the front of the instep is made. Heretofore such a change has always been necessary, and it has resulted in a line or mark or defect which has 40 cheapened the appearance of the hosiery. It is intended by the machine of this invention to knit split work of a very superior grade, and I am enabled to do this and avoid the line or defect referred to by knitting the leg at the auxiliary 45 side.

As most clearly shown in Fig. 9, where the cam 36 is indicated, it is provided with a stem 278 connected to a pin 279 upon a short link 280 which is pivoted at 281 to a bell crank lever 282 pivoted 50 at 283 upon the housing 179. To the opposite end of said bell crank lever is pivoted at 284 a vertical link 285 which at its lower end at 286 is pivotally connected to a lever arm 287 pivoted at 288 upon a suitable bracket or support 288a. The opposite 55 arm 289 of said lever is pivotally connected at 290 to a vertical link 291 which, as shown most clearly in Figs. 4, 4a, 4b, extends downwardly to and is pivotally connected at 292 to a lever 293 pivoted at 293a on the main frame. Said lever has 60 on its free end a pin 294 adapted (as shown in Fig. 4b) to extend through an opening in the main pattern drum 23 and to be engaged by a suitable cam 296 thereon so as at the proper time, through the described connections, to pull out of 65 action the knitting cam 36 when going from the ring top into the leg.

I shall next describe the means for moving a switch cam or so-called flopper cam and an adjacently positioned cam for raising all the needles 70 upon going into the leg and for that purpose shall

refer to Figs. 5, 7, 11, 13, 14, 14a, 14b, 14c, as well as to certain diagrams, as, for example, Figs. 40 and 41.

In Fig. 40 and in Figs. 14, 14a, 14b, 14c, is represented the said switch or so-called flopper cam 5 298 mounted in a bracket 298a fast to the cam plate 17'. The function of said cam is to raise all the long butt needles. At certain times said cam 298 is lifted up out of action and a new cam 299 is moved into action. Said cam 299, as clearly 10 shown, is provided with a stem 300 to a pin on which is connected a coil spring 301 which at its other end is connected at 302 to the housing for the cam, thus tending to move said stem radially inward. Said stem 300 is provided with a cam 15 shaped cut 300a, the function of which is to support the switch or flopper cam 298 through the engagement therewith of the tail piece 300b upon the stem of the said flopper cam. Therefore in the in and out movements of the cam 299, the 20 stem thereof controls the movement of the said flopper cam. To move said cam outward, said stem 300 is provided with a notch 303 which, as most clearly shown in Fig. 13, receives the arm 304 of a bell crank lever pivoted at 305 upon the 25 framing of the carrier ring post 306. The other arm of said bell crank lever is pivotally connected at 307 to a rod 308 that extends downward, as more clearly shown in Figs. 5, 7 and 14, and at its lower end is connected to a lever 309. Said 30 lever 309 is pivoted at 310 upon the framing, and the free depending end thereof 311 rests upon a suitable cam disk 312 upon the main pattern shaft 22. When the said cam 299 is moved into action, as indicated by the hatching in Fig. 41, 35 it raises all the needles (that is to say, it raises all the needles when the knitting of the ring top is completed and the knitting of the leg is to begin); therefore this cam releases the latches of all the needles, thus preparing the needles to 40 knit at the auxiliary side where, as heretofore stated, the leg is knitted in accordance with my invention.

There are yet to be referred to, means for moving the auxiliary cam block and one of its cams 45 into and out of action, means for moving the regular cam block, and the binder mechanism. It is unnecessary to describe at any length the means for moving the regular cam block as the construction is the same as that disclosed in the 50 patent to Gagne, No. 1,673,764. It is unnecessary to refer to the binder mechanism herein shown, because it is the same as that disclosed in the said Gagne patent. Inasmuch, however, as the means for moving one of the cams of the auxiliary knitting set and for moving the auxiliary cam block are somewhat different in their details from those shown in the said Gagne patent, I shall next set forth those differences and in so 55 doing shall refer to Figs. 5, 7, 11, 13, 14, 15.

Referring to Figs. 5, 7, 11, 15, the cam 41 (clearly indicated in Fig. 15) is shown as provided with a stem 313. Said stem has upstanding therefrom a pin 314 in a lengthwise slot 315 provided in a lever 316 pivoted at 317 upon a suitable support 318. The lever 316 and link 316a connecting the lever 100 also operate the yarn lever B on the auxiliary side. Said lever 316 at its outer end is pivotally connected at 319 to a link 320 which at its other end is pivotally connected at 321 to an upwardly extending arm 322. Said arm 322 is mounted for rocking movement on a short shaft 323, and rigid with said arm is another arm 324. To the outer end of said arm 324 is pivotally connected at 325 a downwardly ex- 70 75 75

tending rod 326, shown most clearly in Figs. 5, 7 and 14. At its lower end said rod 326 is pivotally connected at 327 to a lever 328, shown in Fig. 5. Said lever is also pivoted upon stud 5 shaft 133g, and its free end rests upon a suitable cam upon the cam disk 312 already referred to.

In order to move the entire auxiliary cam block, the following means is provided (shown most clearly in Figs. 7, 13, 14, 15). In Fig. 15, the 10 entire auxiliary cam block is indicated at 17. It is mounted for in and out sliding movement upon the plate 17. Said auxiliary cam block 17 has secured thereto a pin 330 extending downwardly through a slot in the plate 17. Pressing 15 against said pin is a lever arm 331 which, as shown most clearly in Figs. 13 and 17, is pivoted at 332 upon the under side of the said plate 17. At its opposite end said lever 331 is pivotally connected at 333 to a link 334, shown most clearly 20 in Figs. 14 and 17. Said link 334 is pivotally connected at 335 to the upright lever arm 336 which is fast upon a short rock shaft 337. Also fast on said shaft 337 is a lever arm 338 which at 339 is pivotally connected to a downwardly extending 25 link 340. As shown most clearly in Figs. 7 and 14, said rod 340 is connected at its lower end to a lever 341. Said lever is likewise pivoted upon the stud 310, and the inner free end of the lever rests upon a suitable cam upon the cam disk 312.

30 Referring to Figs. 5, 7, 14, the link 133 is pivoted at 133a to the bell crank 133b pivoted at 133c on a bracket 133d fast upon the framing. A rod 133e is connected at its lower end to a lever 133f pivoted at 133g, the outer end of the lever 35 133f resting upon a suitable cam upon the cam disk.

I shall next refer to the developments or diagrams Figs. 40 to 47. These show the positions of the various cams during the knitting of the 40 different parts of the stocking or half hose. When knitting on the regular side, the knitting parts of cams 39, 40 are raised slightly above the cams 35, 36, and when knitting on the auxiliary side, the cam 36 is raised slightly above the points 45 of the cams 39, 40. This is done so as not to strain or break the stitches.

The diagram (Fig. 40) shows the position of the parts during the knitting of the ring top 1a of Figs. 1 and 2. The knitting at such time is 50 circular or round and round in the direction of the arrow adjacent said figure. The said knitting is done at the regular side, and therefore the knitting cam 36 is in action. The positions of all the other cams during that operation are indicated in Fig. 40, the cams in action being indicated by hatching.

As already stated, the circular knit part of the leg is knitted at the auxiliary side. The position of the cams therefore is indicated in the diagram, 60 Fig. 41. It will be noted that the knitting cam 36 is shown in full lines as being out of action at that time, and that the hatching upon the cam 105 is done by horizontal lines, instead of the vertical hatching upon the cams which are fully 65 in against the needle cylinder. The hatching upon cam 105 indicates that it has been moved only part way in so as to engage only the long butt needle jacks, missing the short butt jacks. As already described, the purpose of this cam 70 105 is to close the eyelet which otherwise would be formed upon going out of the ring top.

The knitting cams remain in the position indicated in the diagram Fig. 41 throughout the round and round knitting of the leg, that is, 75 down to the commencement of the high splice.

From then onward, the knitting is reciprocating knitting. The knitting of the high splice and the instep portion in advance thereof is indicated by the position of the parts in Figs. 42 and 43, the former of which shows the position of the parts when the stroke of reciprocation is toward the left, viewing said Fig. 42, and Fig. 43 shows the position of the parts when the stroke of reciprocation is toward the right viewing said figure.

10 The position of the parts in knitting the heel pockets 6 is indicated in Figs. 44 and 45, the former showing the position of the parts when the stroke of reciprocation is toward the left in said figure, and Fig. 45 indicating the position of the parts when the stroke of reciprocation is toward the right viewing said figure.

The knitting of the narrow sole by split work is indicated in Figs. 46 and 47, the former indicating the position of the parts when the stroke 20 of reciprocation is toward the left in said figures, and the latter indicating the position of the parts when the stroke of reciprocation is toward the right in said figures.

When the foot is knitted with the suture seams 25 along the midwidth thereof, as indicated in Fig. 3, it is not necessary, as already explained, to use the jacks under the needles, and therefore the jack controlling cams might be omitted or rendered inactive as desired.

30 The purpose of the disk 169 with the cams 167, 168 has been set forth, to the effect that the same controls the reinforcement of the toe. Heretofore it has not been possible in any constructions with which I am familiar to vary the shape of 35 the reinforcement on the toe. In Figs. 1, 2 and 3, I have represented the toe as provided with a second or reinforcing yarn at the area 13. By the construction herein described, the shape and extent of the reinforcing area 13 may be varied 40 as desired. Viewing said figures, it will be noted that the area 13' is left unreinforced. The non-reinforced areas are two in number, namely, the area at the outer side of the big toe and the area at the outer side of the little toe. It may 45 be desired to make the non-reinforced area of greater length lengthwise of the toe of the stocking or of greater width circumferentially of the toe of the stocking. This is possible because of the provision of the cams 167, 168. The lever 50 arm 166 is snapped or moved off the edge of the disks 167, 168 and is moved back on again in the manner already described. The time when the arm 166 is moved back onto the circumferential edge of one of said cams is determined by the 55 positioning of the link on the main pattern chain. By adjusting the distance of the disks 167, 168 toward or from each other, provision is made for varying the width of the reinforcement of the toe portion in a direction around or circumferentially of said toe portion. In other words, the 60 position on the main pattern chain of the proper lug determines the length of the toe reinforcement with respect to the total length of the toe portion, and the circumferential position of the 65 cams 167, 168 determines the circumferential extent of the said toe reinforcement.

Having thus described one illustrative embodiment of the invention, it is to be understood that although specific terms are employed, they 70 are used in a generic and descriptive sense and not for purposes of limitation, the scope of the invention being set forth in the following claims.

I claim:

1. A circular, split work knitting machine hav-

ing a main set of knitting cams, an auxiliary set of knitting cams, means to feed yarns at said two sets of knitting cams respectively, means to knit the heel by narrowing and widening, means to 5 knit the suture seams of the foot at two different levels for each seam, and means to knit into the stocking the float thread formed when the position of such a suture seam is shifted.

2. A circular, split work knitting machine having a main set of knitting cams, an auxiliary set of knitting cams, means to feed yarns at said two sets of knitting cams, respectively, means to knit the heel by narrowing and widening, means to knit the foot by split work having a 15 part of each suture seam of the foot at a level below the inner corners of the heel, and another part at a higher level, and means to knit into the stocking the float thread formed where each suture seam is shifted from said lower level to 20 said higher level.

3. A circular, independent needle, knitting machine provided with a main set of knitting cams, an auxiliary set of knitting cams, means to introduce yarns to the needles at the two sets 25 of knitting cams respectively, a shaft located at the rear of the machine carrying a drum for controlling the take-ups, means carried by said shaft to control the position of the split work suture seams along the side of the foot, and 30 means also carried by said shaft to control the reinforcement constituting the high splice, and the reinforcement of the toe.

4. In a circular knitting machine having independent needles, a plurality of needle operating cams having conflicting operating positions and means operating said cams on relatively angularly disposed paths to replace one cam by the other.

5. A knitting machine having therein means for producing split work throughout desired portions 40 of a stocking including a needle cylinder, a series of independently operated needles, a primary set of knitting cams, an auxiliary set of knitting cams and means for feeding separate yarns to the needles at said primary and auxiliary set of cams, 45 said needles being divided into series having long and short butts, jacks individual to a group of needles at either end of one of said series of needles, said jacks in each group having differentiated butt formations whereby some or all of 50 the jacks in each group may be controlled, and selective means for controlling said jacks.

6. A circular, independent, latch needle knitting machine adapted to knit split-foot stockings including a main set of knitting cams, an auxiliary 55 set of knitting cams, means for feeding a yarn to the main set of knitting cams throughout the knitting of a ring top, heel and toe of a stocking, means for feeding a yarn for knitting the leg and instep of the stocking at the auxiliary knitting cam and means for directing needles knitting the 60 leg of the stocking at the auxiliary cams through the main cam set without clearing the latches of said needles at that cam set.

7. In a circular, independent needle knitting 65 machine adapted to knit split-foot stockings, the combination of a needle cylinder, independent latch needles in said cylinder, a main cam set and an auxiliary cam set, means for feeding a yarn for knitting the ring top, heel and toe of a stocking 70 at the main cam set and means for feeding a yarn throughout the knitting of the leg and instep of the stocking at the auxiliary set of knitting cams, and means for automatically withdrawing one of said main knitting cams at the start of 75 knitting the leg whereby needles which are knit-

ting the leg yarn at the auxiliary side of the machine will pass through the main cam set without clearing their latches.

8. In a circular, independent needle knitting machine adapted to knit split-foot stockings, the combination of a needle cylinder, independent latch needles of said cylinder, a main cam set and an auxiliary cam set, means for feeding a yarn for knitting the ring top, heel and toe of a stocking at the main cam set and means for feeding a 10 yarn throughout the knitting of the leg and instep of the stocking at the auxiliary set of knitting cams, means for automatically withdrawing one of said main knitting cams at the start of knitting the leg, and means movable to an operative position at the start of knitting the leg for clearing needle latches just before said needles pass through said auxiliary cam set, whereby stitches drawn at the auxiliary cam set will not be cast off at the main cam set but thereafter, needles will 15 be prepared for knitting at the auxiliary side of the machine.

9. In a circular knitting machine having independent needles, a pair of needle cams having conflicting operating positions, one of said cams 25 being provided for swinging in a substantially vertical plane and the other cam being so constructed that it slides in a direction substantially at right angles to the plane in which the first cam swings and means for moving either cam out of 30 operative position whenever the other cam is moved to operative position.

10. In a circular knitting machine having independent needles, a pair of needle cams movable to and from operative position, one of said cams 35 being so constructed that when moved to operative position it will move the other cam to inoperative position.

11. In a circular knitting machine having independent needles, a plurality of needle operating 40 cams including one cam swinging in a substantially vertical plane and having resilient means for maintaining it in operative position, another cam movable substantially at right angles to the plane in which the first cam swings and resilient 45 means for maintaining this cam in an operative position and means between the two cams for moving one of the cams to an inoperative position when the other is moved to operative position.

12. In a split-foot knitting machine, a needle 50 cylinder, a series of independent needles therein, a main cam set and an auxiliary cam set, means functioning at said main cam set to feed a yarn to the needles for knitting a ring top, a heel and a toe of a stocking, means at said auxiliary cam 55 set for feeding a single yarn throughout the knitting of the leg and instep of the stocking and means for automatically controlling the functions of said machine from the time a stocking top is transferred to the needles until the completion 60 of said stocking.

13. A split-foot knitting machine adapted to knit a complete stocking in continuation of a transferred top which has been placed on needles of said machine including a needle cylinder, a 65 series of independent needles therein, a main cam set and an auxiliary cam set, means at the main cam set for feeding a yarn throughout the knitting of a ring top, heel and toe of a stocking and means at said auxiliary cam set for feeding a 70 single yarn throughout the knitting of a leg and instep of said stocking, and means functioning under automatic pattern control for bringing said ring top yarn into action at the start of knitting in continuation of a transferred stocking top and 75

for introducing said leg yarn at the auxiliary side of the machine after a few courses have been knitted from said ring top yarn.

14. A circular, independent, latch needle knitting machine adapted to knit split foot stockings including a main set of knitting cams, an auxiliary set of knitting cams, means for feeding a yarn to the main set of knitting cams throughout the knitting of certain parts of a stocking, means for feeding another yarn for knitting the leg and instep of the stocking at the auxiliary knitting cams and means for directing needles which are to knit at the auxiliary cams through the main cam set without clearing the latches of said needles at 10 that cam set including mechanism for moving out of action one of the knitting cams at the main cam set prior to starting the knitting of the leg.

15. A circular, independent, latch needle knitting machine adapted to knit split foot stockings including a main set of knitting cams, an auxiliary set of knitting cams, means for feeding a yarn to the main set of knitting cams throughout the 5 knitting of certain parts of a stocking, means for feeding another yarn for knitting the leg and instep of the stocking at the auxiliary knitting cams and means for directing needles that knit the leg of the stocking at the auxiliary cam through the main cam set without clearing the latches thereof, including means for moving out of action upon going into the knitting of the leg, a knitting cam at the main cam set, and cam means for raising all the needles upon going into the knitting of 10 the leg.

ROBERT H. LAWSON.
